[57] CLAIM

The ornamental design for a faucet set, as shown.

DESCRIPTION

FIG. 1 is a front elevational view of the faucet set showing our new design;

FIG. 2 is an end elevational view;

FIG. 3 is a rear elevational view;

FIG. 4 is a top plan view;

FIG. 5 is an end elevational view showing the end opposite to that shown in FIG. 2;

FIG. 6 is an end elevational view of the faucet spout with one of the handles removed for clarity of illustration; and

FIG. 7 is a bottom plan view.
